(57) **CLAIM**

The ornamental design for a bedside commode, as shown and described.

DESCRIPTION

FIG. 1 is a perspective view of a bedside commode, in an open configuration, showing the new design;

FIG. 2 is a perspective view of the bedside commode, in a closed configuration, showing the new design;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top plan view thereof.

The broken line portions shown in FIGS. 3 and 4 are for the purpose of illustrating portions of the bedside commode that form no part of the claimed design.
